UNITED STATES PATENT OFFICE.

EMIL LEHMANN, OF HAMMOND, INDIANA, ASSIGNOR TO ENTERPRISE BED COMPANY,
OF HAMMOND, INDIANA, A CORPORATION OF ILLINOIS.

TENT-BED.

947,341.

Specification of Letters Patent. Patented Jan. 25, 1910.

Application filed February 15, 1909. Serial No. 478,894.

To all whom it may concern:

Be it known that I, EMIL LEHMANN, a citizen of the United States, residing at Hammond, in the county of Lake and State of Indiana, have invented certain new and useful Improvements in Tent-Beds, of which the following is a specification.

My invention relates to a folding tent bed and has for its object to provide a tent bed for campers, prospectors, soldiers and the like, which, when it is set up, forms a bed that is raised above the ground and that is completely covered by an inclosing tent, so as to protect the sleeper from the weather and from insects, and which can be collapsed and folded up into small compass and into a convenient shape for transportation.

A principal object of the invention, to be more particular, is to provide a tent bed of this sort in which the bed section and the tent section and legs constitute together a single, integral structure of which the folding or collapsing parts are so related to each other that the device may be folded longitudinally into a relatively thin, narrow parcel without the detachment of the parts and by simple manipulations that can be quickly and easily effected.

The character of the device is such that it may also, in time of need, be used as a stretcher.

The invention has for other objects such new and improved constructions in tent beds and the like as will be described in the following specification and particularly set forth in the claims appended thereto.

A preferred embodiment of the invention is illustrated in the accompanying drawings, wherein—

Figure 1 is a side elevation of the tent bed set up. Fig. 2 is a cross-section on line 2—2 of Fig. 1, looking in the direction of the arrows. Fig. 3 is a longitudinal section on line 3—3 of Fig. 2, looking in the direction of the arrows. Fig. 4 is a longitudinal section taken on the same line, but illustrating the tent section in its collapsed position. Fig. 5 is a sectional plan taken on line 5—5 of Fig. 4. Fig. 6 is a side elevation of the device completely collapsed and packed up ready for transportation. Fig. 7 is an inverted plan view of the same. Fig. 8 is a detail of the detachable ridge pole, which may be used as a strut between the

supporting devices of the tent. Fig. 9 is 55 a detail elevation, with parts in section, illustrating the construction of the tent supports. Fig. 10 is a front view of the same parts; and Figs. 11 and 12 are similar detail views of a modified form of construction. 60

Like characters of reference indicate like parts in the several figures of the drawings.

Referring to the drawings, the bed section, as I have termed it, consists of the side 65 rails 15, to which is secured a strip 16 of some strong fabric, such as canvas, to form the bed bottom.

Supporting devices are provided for the side rails which preferably may be collapsed 70 and also folded against the bed section. I have shown at each end of the device a pair of legs which are pivoted together. These legs may be of any construction to effect the desired result. Leg 17 is shown as consisting of a single piece of wood hinged by the plates 18 to one of the side rails, the plates being pivoted to the latter at 19. The other leg consists of two pieces of wood 20, 21, connected by the curved straps 22 in such a 80 way as to leave a space in which is pivoted by bolt 23 the other leg 17. The upper part 20 of the two-part leg is hinged to its side rail by means of hinge plates 18, identical with those referred to. A hook 24 is 85 attached to one of the legs so as to hook into a staple 25 on the other. By this arrangement the legs may be folded up against the bed section and then collapsed in the manner to be described hereafter. 90

The tent consists of a fabric cover 26 of any suitable size and shape, which is securely and permanently attached to the side rails 15, at the sides of the device, and to the fabric bed bottom at the ends. The cover 95 is formed on each side with an opening, these openings being closed by flaps 27, which may be provided with eyelets 28 for buttoning the flaps to the carriage buttons 29 on the side bars. If desired, the tent 100 may have only one opening and flap. This covering with its flaps constitutes a complete tent or housing over the bed which may be closed when desired. Above the flaps are straps 30 having eyelets 31, and 105 hooks 32, so that the flaps may be held rolled up, as indicated in Fig. 1 by the dotted line 33.

For supporting the cover or tent I provide supporting devices which I shall term hoops, intending by that term any sort of bowed support extending from one side of the bed 5 to the other. These devices are so constructed and so connected with the bed that when they are set up their engagement with the bed and with the cover puts the cover under tension, which holds the supports 10 from accidental displacement. The hoops are also so constructed and connected with the bed that they may be folded down upon the bed and also folded with the bed when it is collapsed longitudinally. I have shown one 15 of these hoops at each end of the device. The hoop consists of the upright or side rods 34, provided with rings 35 at their lower ends, which rings extend over guide rods 36, there being one of these at each corner of 20 the bed; and of the diagonally placed or roof supporting rods 37, which are hinged to rods 34 and at their other ends are provided with rings 38 or other means for hinging them together. I have shown two suitable 25 ways of constructing the hinge between rods 34 and rods 37. One form is shown in Figs. 9 and 10. Rod 34 has secured to its upper end the sleeve 39, in which is pivoted the bent end 40 of rod 37, the sleeve 30 having a slot on its inner face to allow the turning of rod 37. The full line position (Fig. 9) is the position which the roof supports 37 take when the tent bed is set up. The dotted line position shows the position 35 of the parts when the hoop is collapsed for packing.

Another form of hinge is illustrated in Figs. 11 and 12. The upright rod 41 is formed with a loop or ring 42, in which seats 40 the inturned end 43 of a loop 44 on the roof supporting rod 45. In this case also the full line position shows the normal supporting position of the hoop and the dotted line position its collapsed arrangement. 45 The end of loop 44 abutting against rod 41 prevents the roof supporting rod from turning too far. The hoops are preferably so connected with the bed that when they are set up they put the cover under sufficient 50 tension to prevent the accidental displacement of the parts, the arrangement being such, however, that the hoops may be folded down and the tent section collapsed without detaching any part of the device. By 55 means of the rings 35, it will be seen, the hoops slide on the guides 36. When at the inner ends of the guides, the hoops stand, preferably, at a slight inclination from the vertical, as shown, thus putting the cover or tent under some tension. This tension is relieved when the hoops are slid back on the guides and the guides are preferably provided with the offsets 46 to allow the easy 60 turning of the rings when the hoops are folded down upon the bed bottom. If de-

sired, the spaces between the guide rods 36 and the side rails may be small enough so that there is a little friction between the rings 35 and the side rails, which will also hinder the accidental slipping back of the hoops. 70

In order to brace the portions of the cover at the sides of the flaps, diagonal braces 47 may be used, these braces being slidable on rods 34, as, for example, by being provided 75 with the rings 48, which abut against stop pins 49 on rods 34. The upper ends of the braces are preferably bent over, as at 50, and secured to the cover 26. The rods 34 may be sewed to the cover 51 and the rods 33 37 at 52.

I preferably provide a removable ridge pole 53, consisting of a stick and having its ends grooved at 54 and which may be placed between the hoops when the tent bed has 85 been set up. It is not absolutely essential to use this ridge pole, but it is desirable to do so, as it serves as a strut for the upper end of the hoops and also supports the covering between the same. The grooved ends 90 of the pole 53 engage with the rings at the upper end of rods 37.

The operation of the tent bed, when constructed as above described, is as follows: Supposing the device to be set up as shown in Figs. 1 and 3, in order to collapse it for transportation the ridge pole, when that is used, is first taken out and then the hoops supporting the covering are pushed back to the outer ends of guides 36 and are then folded down with the cover upon the bed bottom. This position of the parts is shown in Fig. 4. The hooks 24 are detached from their staples and the whole device, bed section, legs and collapsed tent section, can thereupon be collapsed or folded longitudinally. The hoops fold with the bed section because of the hinged connection between the rods 37 and the hinge formed by rings 35 and offsets 46. The hoops may also collapse at the hinges between rods 34 and rods 37, taking the position shown in dotted lines in Fig. 5. In this way the cover and its supports can be neatly packed away within a sort of sack formed by the fabric bed bottom. The legs may then be folded up, so that the collapsed tent bed takes the shape shown in Figs. 6 and 7. To set up the tent bed, this operation is reversed. 115

It will be seen that the device constitutes a single, integral structure (with the exception of the ridge pole, which may or may not be used). It may be unfolded or folded up by a very simple manipulation of the parts and without the necessity of making any detachments. There are no small, loose parts to become lost. The device, when folded up, makes a long, thin parcel which will easily go into a wagon or a boat and in which the slack of the cover and the more 125

easily breakable supports for the same are securely and neatly packed away in a sort of sack formed by the bed bottom.

I do not limit myself to the particular forms, constructions and devices shown and described, as modifications might be devised which would come within my invention as defined by the claims herein. Certain of the parts have been described as made of wood. The whole structure could be of metal, if desired.

While the device is intended to be used particularly as a bed, it could be used also as a stretcher, in which case the handles 54 15 may be provided, which handles as shown are merely continuations of the side bar. It is optional to construct the device with handles or not.

I claim:

1. In a tent bed, the combination with a 20 bed section, of a tent section comprising a cover attached to the ends and sides of the bed section, and supports for the cover, said tent section being connected to the bed section so that it folds down upon the same and said bed and tent sections, when the former is folded down upon the latter, being foldable longitudinally.

2. In a tent bed, the combination with a 25 bed section, of a tent section comprising a cover and supports for the same which are movably but non-detachably connected with the bed section, said supports being foldable down upon the bed section, and said sections being foldable longitudinally of the bed section.

3. In a tent bed, the combination with a 30 bed section, of a tent section comprising a cover, and supports for the cover at each 40 end of the bed, said supports being slidably connected with the bed section, whereby they may be folded down upon the bed section or set up so as to support the cover, said tent section and bed section being foldable longitudinally of the bed.

4. In a tent bed, the combination with a 45 folding bed section, of a tent section comprising a cover attached to the bed section, and supporting devices for the cover, said supporting devices being movably connected with the bed section so that they may be set up to support the cover or folded down upon the bed section, and being also themselves collapsible so as to fold with the bed section without detachment therefrom.

5. In a tent bed, the combination with a 50 bed section, of a cover attached to said bed section, supporting devices for said cover, and guides on the bed upon which the supporting devices are slidably mounted, said supporting devices adapted in one position on the guides to support the cover, and in another position to be folded down on the bed section.

6. In a tent bed, the combination with a 55

bed section, of a cover secured to the bed section, supporting hoops for the cover having rings on their lower ends, guides on the bed section for said rings, and means on said guides constituting, with said rings, hinges 70 whereby the hoops may be folded down on the bed section.

7. In a tent bed, the combination with a 75 bed section, of a cover secured to the bed section, supporting hoops for the cover having rings on their lower ends, and guides on the bed section for said rings, said guides provided with off-sets, substantially as and for the purpose described.

8. In a tent bed, the combination with a 80 bed section which is foldable longitudinally, of a cover secured to the bed section, supporting hoops for said cover, and guides with which said hoops are slidably connected, said hoops being foldable upon the bed, 85 and being also foldable longitudinally therewith.

9. In a tent bed, the combination with a 90 bed section, of a tent section comprising a cover secured to the bed, supporting hoops for the cover, one at each end of the bed section, which hoops are foldable upon the bed, and which when set up engage the cover and a ridge pole adapted to be put in place between the hoops when the device is set up, 95 said bed section and hoops being foldable together when the hoops are folded down upon the bed.

10. In a tent bed, the combination with a 100 longitudinally foldable bed section, of a tent section comprising a cover, and hoops, one at each end of the bed section which support the cover and are foldable upon the bed section, said hoops being hinged at their middle points. 105

11. In a tent bed, the combination with a 110 longitudinally foldable bed section, of a tent section comprising a cover, and hoops, one at each end of the bed section which support the cover and are foldable upon the bed section, said hoops being hinged at their middle points by universal joints, and at points on each side of their middle points.

12. In a tent bed, the combination with a 115 bed section, of a tent section comprising a cover, and supporting hoops for the same, said hoops consisting of side rods and roof supporting rods hinged to the side rods, and hinged to each other by universal joints, 120 said side rods being foldably connected with the bed bottom.

13. In a tent bed, the combination with a 125 bed section which folds longitudinally, supports for same which collapse and also fold up against the bed section, a tent section comprising a cover attached to the bed section, and a hoop at each end of the bed section to support said cover, said hoops being foldable upon the bed section and being also foldable longitudinally, and guiding rods on 130

- 1 said bed section with which said hoops are
2 slidably engaged.
- 3 14. In a tent bed, the combination with a
4 bed section, of a tent section comprising a
5 cover, supports for the same at each end of
6 said bed section, and braces for the sides of
7 said cover which are movably connected with
8 the cover supports, said supports being fold-
9 able.
- 10 15. In a tent bed, the combination with a
11 bed section, of a tent section comprising a
12 cover, and hoops at each end of the bed en-
13 gaging the cover, and movably connected
14 with the bed section, said supports being
15 foldable down upon the bed, and longitudi-
16 nally, and braces for the sides of the cover,
17 which are slidably mounted on the supports.
- 18 16. In a tent bed, the combination with a
19 bed section, of a tent section comprising a
20 cover and cover supports, said supports com-
21 prising two rods, one of said rods formed
22 with a ring, the other of said supports pro-
23 vided with a loop having an inturned end
24 which seats in the ring of the other member,
25 said loop forming a stop which abuts the
26 other member so as to limit the pivoted
27 movement of one member upon the other.
- 28 17. In a tent bed, the combination with a
29 bed section, of a tent section comprising a
30 cover attached at the edges to the bed sec-
31 tion, and foldable supporting devices for the
32 cover which are connected to the cover and
33 have slidable connection with the bed section
34 lengthwise thereof, whereby the lower ends
35 of said supporting devices may at will be
36 swung to a position to brace said supports
37 against the extended cover so as to support
38 the same, or in the opposite direction so as
39 to collapse with the cover.
- 40 18. In a tent bed, the combination with a
41 foldable bed section, of a tent section com-
42 prising a cover attached at the edges to the
43 bed section, and supporting devices for the
44 cover which are connected with the cover
45 and are slidably connected with the bed, said
46 supporting devices being foldable down
47 upon the bed section and being foldable with
48 the bed section.
- 49 19. The combination with a bottom sec-
50 tion, of a cover secured thereto, and cover
51 supports hinged to the bottom section and
52 arranged to be held in upright position by
53 the tension on the cover resulting from the
54 raising of said supports to upright position.
- 55 20. The combination with a bottom sec-
56 tion, of a cover secured thereto, and cover
57 supports hinged to the bottom section and
58 arranged to be held in upright position by
59 the tension on the cover resulting from the
60 raising of said supports to upright position,
61 said supports, cover and bottom section be-
62 ing foldable lengthwise of said bottom sec-
63 tion.
- 64 21. The combination with a bottom sec-
65 tion, of a cover secured thereto, and cover
- 1 supports having a pivotal connection to the
2 bottom section and slidable lengthwise there-
3 of, whereby in one position said cover sup-
4 ports will be diagonally braced against said
5 cover so as to be held in upright position by
6 the tension on the cover resulting from the
7 raising of said supports to upright position
8 and in another position said supports will
9 collapse with said cover upon said bottom
10 section.
- 11 22. The combination with a bottom sec-
12 tion, of a cover secured thereto, said cover
13 comprising a top portion and end walls ex-
14 tends outwardly and downwardly in op-
15 posite directions from said top portion, and
16 cover supports pivotally connected with the
17 bottom section and arranged to be at will
18 folded down upon the bottom section or
19 swung up into engagement with the cover at
20 the angles between the end walls and the top
21 of said cover and to be held in such position
22 by the resulting tension on the cover.
23. The combination with a bottom sec-
24 tion, of a cover secured thereto and comprising
25 a top and end walls extending diagonally
26 downward and outward from said top in op-
27 posite directions, and cover supports pivot-
28 ally secured to the bottom section and slid-
29 able at their lower ends lengthwise of the
30 bottom section, whereby the upper ends of
31 said cover supports may be raised into en-
32 gagement with the cover at the angles be-
33 tween the top and end walls thereof and the
34 lower ends of said supports may be moved
35 lengthwise of the bottom section, so that at
36 will said supports will either be diagonally
37 braced against said cover so as to be held in
38 upright position by the resulting tension on
39 said cover or may be folded upon said bot-
40 tom section with said cover.
- 41 24. The combination with a longitudinally
42 foldable bottom section, of cover supports
43 which are transversely foldable relative to
44 the bottom section and also longitudinally
45 foldable with respect thereto connected with
46 said bottom section, and means for holding
47 said cover supports in upright position when
48 said bottom section is extended.
- 49 25. The combination with a bottom sec-
50 tion, of a cover attached thereto, cover sup-
51 ports arranged to engage the cover at sub-
52 stantially fixed points when the structure is
53 extended, and means for connecting the
54 lower ends of the cover supports at different
55 points lengthwise of the bottom section.
- 56 26. The combination with a longitudi-
57 nally foldable bottom section, of a cover at-
58 tached thereto, and cover supports connected
59 with said bottom section so as to be foldable
60 lengthwise upon said bottom section and
61 transversely therewith.

65 H. L. PECK.

It is hereby certified that in Letters Patent No. 947,341, granted January 25, 1910, upon the application of Emil Lehmann, of Hammond, Indiana, for an improvement in "Tent-Beds," errors appear in the printed specification requiring correction, as follows: Page 2, line 80, after the word "cover" the word *at* should be inserted, and page 4, line 26, the word "pivoted" should read *pivotal*; and that the said Letters Patent should be read with these corrections therein, that the same may conform to the record of the case in the Patent Office.

Signed and sealed this 15th day of February, A. D., 1910.

[SEAL.]

C. C. BILLINGS,
Acting Commissioner of Patents.
